UNITED STATES PATENT OFFICE.

AUGUST F. LUZZI, OF CLEBURNE, TEXAS.

SPRING-HEEL.

No. 857,816.

Specification of Letters Patent.

Patented June 25, 1907.

Application filed August 1, 1906. Serial No. 328,790.

To all whom it may concern:

Be it known that I, AUGUST F. LUZZI, a citizen of the United States, residing at Cleburne, in the county of Johnson and State of Texas, 5 have invented certain new and useful Improvements in Spring-Heels, of which the following is a specification.

This invention relates to a resilient supporting means adapted to be placed within the 10 heel of a shoe whereby a yielding support is formed for the heel of the wearer. This results in breaking the jars or shocks caused by walking on pavements and also permits the 15 foot to adjust itself naturally in the shoe to diminish any tendency toward wearing the heel unevenly.

In general the invention consists essentially of a plate fitting loosely within the heel 20 of a shoe and having a spring tongue formed 25 in conjunction therewith, and a spring located under the spring tongue and having a peculiar connection therewith.

For a full understanding of the invention 30 and the merits thereof and also to acquire a 25 knowledge of the details of construction of the means for effecting the result, reference is to be had to the following description and accompanying drawings, in which:

Figure 1 is a side elevation of the invention 35 showing a shoe in dotted lines; Fig. 2 is a bottom plan view of the same; Fig. 3 is a longitudinal sectional view through the spring heel; Fig. 4 is a bottom plan view of a modified form; Fig. 5 is a similar view of a second modification.

Corresponding and like parts are referred 40 to in the following description and indicated in all the views of the drawings by the same reference characters.

The numeral 1 designates a plate formed of 45 metal or other spring material and having a shape corresponding to the shape of the heel of a shoe, one side having a curved and approximately U-shape, as seen at 2, while the 50 opposite side 3 is straight and extends transversely across the shoe. The tongue 4 is cut or stamped from the plate 1 and preferably has a shape corresponding to that of the plate. The edges of the tongue 4 are slightly spaced 55 from the adjacent portions of the plate 1 and the said tongue is bent outwardly so as to have a spring action and tend to force the heel of the foot of the wearer upwardly. In order to hold the plate securely in position 60 within the shoe, teeth 5 are stamped from the plate 1 adjacent the straight edge 3 and are

bent downwardly and embedded in the inner sole of the shoe when the device is in use. A covering 6 of leather or similar flexible material is placed over the upper face of the 60 plate 1 and is normally raised upward, as indicated in Fig. 1, by means of the spring tongue 4. In the present instance, it will be observed that the covering 6 extends somewhat beyond the straight edge 3 of the plate 65 1 and forms a cushion between the foot of the wearer and the metallic portions of the heel. This leather covering is held in position by means of a strip 7 of metal or similar material, the ends of which are passed through the 70 leather and then slipped around the tongue 4 and are then bent inwardly as indicated at 8 in Fig. 2 so as to engage with the base or lower portion of the tongue 4. For purposes of ventilation, an opening 9 may be formed 75 in the tongue 4 and a corresponding opening made in the flexible covering 6.

A spring 10 is located beneath the tongue 4 and tends to coöperate with the same to form a resilient bearing for the foot of the 80 wearer. This spring is shown in the form of a coil spring which tapers toward the lower end thereof so as to fit closely against the tongue 4 when compressed. In the preferred form of the invention shown in the 85 first three figures of the drawings, a pair of parallel and longitudinal cuts are formed in the upper portion of the tongue 4 and the strap 11 between the cuts pressed downwardly the end of the spring 10 being passed 90 through the opening thus formed. It will be observed that the portion of the spring 10 immediately over the strip 11 is flattened as seen at 12 and this flattened portion coöperates with the strap 11 to hold the base of the 95 spring normally against the lower face of the tongue 4. However, the spring 10 has a hinged connection with the tongue and if found necessary can be swung outwardly as indicated by dotted lines in Fig. 3. This 100 would enable a supplemental spring to be placed within the main spring should the latter not prove strong enough.

In the modification shown in Fig. 4, the end of the spring 10 is bent outwardly at 13 105 and passed over a strap 14 formed in the plate 1 adjacent the straight edge 3 by means of two parallel and transverse cuts. In this figure, it will be also observed that the opposite side of the spring 10 is held against the 110 tongue 4 by an ear 15 stamped therefrom.

In the form shown in Fig. 5 one side of the

spring is held in position by means of a strap 11^a similar to the strap 11 of the preferred form, while the end of the spring is engaged by an ear 16 at the base of the tongue 4. 5 With this latter construction, the spring 10 could be swung outwardly in the manner similar to that described in connection with the preferred form by first turning it to throw the end of the spring out of engagement with the ear 16. In all of the forms of the invention, however, the spring is detachably connected to the tongue 4 so as to be readily replaced if necessary.

Having thus described the invention, what 15 is claimed as new is:

1. In a device of the character described, the combination of a plate fitting within the heel of a shoe and provided with teeth for holding it in position, the said plate having a 20 spring tongue stamped therefrom and bent slightly outward, a flexible covering fitting over the tongue, and a strip of material for

holding the flexible covering in position, the ends of the before mentioned strip being passed through the flexible covering and bent 25 into engagement with the base of the tongue.

2. In a device of the character described, the combination of a plate fitting within the heel of a shoe and having a tongue formed in conjunction therewith and bent slightly outward, the said tongue being formed with a strap located between two parallel cuts, and a coil spring fitting under the tongue and engaging with the strap, the portion of the spring adjacent the strap being flattened and 30 coöperating with the strap to prevent any pivotal movement of the spring and hold the same securely against the tongue.

In testimony whereof I affix my signature in presence of two witnesses.

AUGUST F. LUZZI. [L. S.]
